UNITED STATES PATENT OFFICE

2,515,365

FLEXIBLE DRILL PIPE

John A. Zublin, Saugus, Calif., assignor of one-fifth to Edward Adolphus Zublin, one-fifth to Casper Leonid Zublin, both of Los Angeles, Calif., and one-fifth to Sonia (Catherine) Lynn-Thomas, New York, N. Y.

Application March 31, 1947, Serial No. 738,335

1 Claim. (Cl. 255—28)

1 The present invention relates to a novel form of flexible drill pipe.

Flexible drill pipe is employed in the drilling of bores deviating from existing well bores, more particularly in accordance with the method of my United States Patent 2,382,933. Heretofore, the resilient flexible metal drill guide has been constructed by slotting a straight drill pipe along a line following a spiral which runs with the desired pitch around the length of the pipe section. Unslotted end portions are left for threading and to provide appropriate means for connecting the drill guide or stem into the drill string. Such a form of flexible drill guide is disclosed in my prior Patents 2,336,338 and 2,344,277.

The present invention contemplates an improvement upon a flexible drill pipe structure and has as its specific object to provide a flexible drill pipe structure that is not subject to destruction or unwanted deformation in use.

Many oil wells are now drilled to depths deeper than 4000 feet and, therefore, there is often considerable variation in the application of weight as well as tension on a spirally slotted flexible drill pipe located in juxtaposition to the bit at the bottom of the well.

Experience has shown that a helically slotted flexible drill pipe with a smooth walled slot following a spiral around the length of the pipe will often become distorted when excess weight is imposed on the drill stem, either occasioned because of inaccuracy of the weight indicating instrumentalities at the surface of the well or through unintentional carelessness of the driller. The application of excess weight to the flexible drill stem having the smooth walled spiral slot therein results in the distortion of the flexible pipe occasioning expansion of the helices thereof. Furthermore, the application of excess tension sometimes permits the flexible drill pipe to be stretched out of shape, defeating its intended purposes.

It is, therefore, the general purpose and object of the present invention to provide a flexible drill pipe so slotted and constructed that the pipe retains the desirable flexibility and resiliency to bend along its longitudinal axis, but which is resistant to deformation under compression, torque, and preferably also under tension.

The objects of the present invention are obtained through the provision of an appropriately formed slot which extends spirally around the drill pipe. The details of the invention will become apparent as the description proceeds, which will be given by reference to the accompanying drawings which form a part hereof and in which:

2 Figure 1 is a side elevational view of a portion of a section of a flexible drill pipe conforming to the present invention;

5 Fig. 2 is a section on the line 2—2 of Figure 1, with diagrammatic representation of the forces which tend to effect distortion of the flexible drill stem;

10 Fig. 3 illustrates the positioning of the drill stem of the present invention in an oil well where it is employed to drill a deviating bore.

In Figure 1, there is superimposed on the drill pipe 16 a force diagram which may be referred to to explain what normally happens to a spirally slotted drill pipe when excessive pressure is applied thereto.

15 The compressive force indicated by the vertical arrow P_1 in the force diagram of Figure 1, normally exerts itself against a smooth surface of a spiral slot, such as shown in Fig. 9 of my prior Patent 2,336,338. This compressive force is divided into the component force P_2 in the direction of the arrow so designated in the force diagram of Figure 1, and the component force P_3 designated by the arrow thus marked in the force diagram of Figure 1. It will be observed that the component force P_2 is at right angles to the normal helical slot whereas the component force P_3 is parallel to the helical slot.

20 When excessive weight is applied to a drill stem such as 16, this weight creates pressure contact between the elastic sections of the flexible drill stem above and below the helical slot. Therefore, if the excessive weight is represented by the pressure P_1 which is applied equally and symmetrically around the contour of the drill pipe, an equal number of component forces P_2 and P_3 become effective along the spiral, forming a smooth line of contact between the flexible sections of the drill stem above and below the slot. By reference to Fig. 2 it will be clearly seen how the component forces P_3 arrange themselves tangentially around the circumference of the pipe along the slot.

25 These component forces P_3 together form a powerful leverage which tends to open the drill pipe along the helical slot and to increase its diameter. If excess pressure in an amount sufficient to open the flexible drill pipe is imposed thereon, the upper section of the flexible drill pipe will telescope over the next lower section causing destruction of the unit of the flexible drill pipe.

30 Even a lesser expansion than effective to cause telescoping of the section will nevertheless in some instances destroy the unit because the metal is pulled away from the high pressure rubber lining, indicated at 15 of Fig. 2, of the flexible **35** drill pipe. The high pressure rubber lining of

the flexible drill pipe, it will be appreciated, is unable to follow the excessive expansion in diameter of any given portion of the helically slotted drill pipe and thus becomes deprived of its metal backing, rendering it likely to burst under the inside fluid pressure of the hydraulic fluid employed to drive the bit at the lower end of the drill stem.

The disadvantages just described are those which have attended the use of the flexible drill pipe having a smooth walled spiral slot. As heretofore indicated, it is a specific purpose of the present invention to so slot the flexible drill pipe that the portion thereof above the slot at any given point cannot move circumferentially in relation to the section below the slot at that point thus facilitating rotation of the flexible drill pipe either in a curved bore or a straight bore.

Specifically, it has been found that a spiral slot so cut in the wall of the drill pipe 16 as to provide intermeshing teeth above and below the slot effectively solves the difficult problem presented.

An embodiment of the invention is shown in Figure 1, wherein the metal drill pipe 16 is provided with the slot 17 so cut through the wall of the drill pipe 16 as to form the locking dove-tail type teeth 18 and 19. It will be appreciated that the slot 17 extends generally along the path of the spiral line 20. When employing a flexible drill pipe conforming to the embodiment of Fig. 1, the spirally extending slot of "dove-tail" pattern 17 will permit the necessary bending along the longitudinal axis of the flexible drill pipe 16 to permit the same to effectively function in the drilling of deviating bores. The dove-tail teeth 18 and 19 will, however, effectively interlock the sections of the drill stem 16 above and below the slot and prevent any movement of these sections in respect to each other beyond the amount of movement allowed by the width of the slot. These slots are adapted to be cut by gas torch and their dimensions can be closely controlled and held within prescribed limits. A pattern yielding intermeshing dove-tail teeth, such as teeth 18 and 19 of Fig. 1, can be readily cut and accurately follow a spiral or any desired pitch along the metal pipe. This may be accomplished through the employment of either an automatic or non-automatic torch, both of which are readily available on the market.

It will be appreciated that the width of the slot 17 will determine the amount of relative movement between the opposite dove-tailed teeth 18 and 19 of the pattern and, therefore, the width of the slot functions to regulate the over-all flexibility of the slotted pipe.

In practical tests, it has been found that a slot varying from $\frac{3}{8}$ of an inch to $\frac{5}{8}$ of an inch in width and having a pitch of the spiral of about nine (9) inches for a four and

one-half (4½) inch diameter drill pipe of hardened steel will yield a flexible resilient drill stem having the capacity to bend into a curve of an eighteen (18) foot radius, while at the same time providing a drill pipe having a compressive strength three (3) times greater and a tensile strength some ten (10) times greater than a comparable drill pipe provided with an ordinary smooth walled spiral slot.

From the foregoing description it will be appreciated that, in accordance with the present invention, there is provided a flexible drill pipe adapted to be employed as a drill guide in the drilling of deviating bores which will be safeguarded against distortion and destruction in use.

Having thus described my invention, I claim:

An elongated, resilient, flexible, metal drill pipe comprising a tubular metal pipe having a slot of appreciable and uniform width through its wall extending in a generally helical path around and along the pipe, said slot deviating from a true helical path to provide along the sides of the slot intermeshing and loosely interlocking teeth of dovetail configuration, each of said teeth having straight flat side edges which diverge from the root of the tooth to terminate in a straight flat end edge which is substantially parallel to the generally helical path of said slot, the edges of said teeth being spaced from adjacent teeth by the normal width of the slot while the pipe is in unstressed condition, and the edges of said teeth engaging adjacent teeth to limit the extent of resilient deformation of said pipe upon application of tensile, compressive or torsion stressed to said pipe.
